CUTTER FOR HYDRAULIC DREDGES

Loudon E. MacFadyen, Easton, Pa., assignor to
Taylor-Wharton Iron & Steel Company, High
Bridge, N. J., a corporation of New Jersey

Application October 6, 1934, Serial No. 747,233

4 Claims. (Cl. 37—67)

The invention relates to rotary cutting or excavating apparatus for hydraulic dredges and particularly to means in association therewith for guarding the suction head or nozzle and sizing 5 the excavated material that enters the suction line.

The principal object is to simplify foundry and machine problems and to provide a relatively inexpensive cutterhead having means cast integral therewith that will reject spoil that is too 10 large for passage through the suction line and do it in such way as to prevent clogging of the suction head or nozzle, the guard comprising spaced arms springing radially inward from the cutter spider and having an orbital path of 15 movement in spiral order of arrangement in close proximity to and across the mouth of the suction head.

A preferred embodiment of the invention is 20 illustrated in the accompanying drawing, wherein:

Figure 1 is an outer end elevation.

Fig. 2 is a side elevational view partly broken away and partly in section, the better to show 25 the construction and arrangement of the guard integers.

Fig. 3 is an inner end elevational view with the suction head in section.

The cutterhead 5 is equipped, as usual, with 30 cutting and agitator arms 6 having shaft mountings 7 and 8. The latter is a back ring or annulus which, according to my invention, is integrally formed with inwardly directed guard fingers 9 in spiral order of arrangement addressed 35 to the direction of travel. Fingers 9 have relatively blunt heel portions 10 and relatively sharp or angular toe portions 11. The fingers are of

length adequate to guard the suction head or nozzle 12 and their spaced relation and helical arrangement are such that at times they function in pairs, that is to say, two of them are in lapping relation with the suction head. 5

The merit and effect of the described construction, arrangement and coordination of parts, is to prevent clogging of the suction line by the instant rejection of masses of rock or spoil that would choke the line. 10

Having described the invention, I claim:—

1. In a hydraulic dredge, in combination, a suction head, a cutterhead in operative relation therewith, and a back ring on the cutterhead having inwardly directed radial guard fingers 5 with free ends in lapping relation with the suction head.

2. In a hydraulic dredge, in combination, a suction head, and a cutterhead in operative relation therewith, the back ring of the cutterhead 20 having inwardly directed spirally disposed stubs whose free ends trail the cutter across the mouth of the suction head.

3. In a hydraulic dredge, in combination, a suction head, a cutterhead including a back ring 25 whose inside diameter is sufficient to clear the suction head, and stub members inwardly and radially sprung from the back ring and effective to size spoil entering the suction head.

4. In a hydraulic dredge, in combination, a 30 suction head, a cutterhead including an integral back ring in operative relation therewith, and guard fingers sprung radially inward from the back ring of the cutterhead and having relatively blunt heel portions and relatively sharp toe portions. 35

LOUDON E. MACFADYEN.
